UNITED STATES PATENT OFFICE.

NAPOLEON ST. PETER, JR., OF FAIRFIELD, MAINE, ASSIGNOR OF TWO-THIRDS TO DAVID KING, OF FAIRFIELD, MAINE, AND JOSEPH CARI-VEAU, OF WATERVILLE, MAINE.

STREET-CLEANING APPARATUS.

No. 810,362.

Specification of Letters Patent.

Patented Jan. 16, 1906.

Application filed March 2, 1904. Serial No. 196,158.

To all whom it may concern:

Be it known that I, NAPOLEON ST. PETER, Jr., a citizen of the United States, residing at Fairfield, in the county of Somerset and State 5 of Maine, have invented new and useful Improvements in Street-Cleaning Apparatus, of which the following is a specification.

This invention relates to street-sweepers.

The objects of the invention are to improve 10 and simplify the construction of such devices.

With the foregoing objects in view the invention resides in the particular combination and arrangement of parts and in the precise 15 details of construction hereinafter described and claimed as a practical embodiment thereof.

In the accompanying drawings, forming a part of this specification, Figure 1 is a side 20 elevation of the machine. Fig. 2 is a rear elevation thereof. Fig. 3 is a section on line 3 3, Fig. 1. Fig. 4 is a section on line 4 4, Fig. 1. Fig. 5 is a detail view of one of the sweeping-rolls. Fig. 6 is a perspective view 25 of the roll-adjusting lever and its connections; and Fig. 7 is an enlarged section through the spraying apparatus, the spray being shown in elevation.

Referring to the figures by numerals of reference, 1 is the platform of a motor-propelled vehicle, and arranged on this platform is a receptacle 2, having a perforated dome 3 on the top thereof, which is partitioned from the receptacle by means of gauze 4. A sponge 35 5 or other like material is arranged within the dome and supported therein by the gauze 4, and this sponge is adapted to be kept moist, so as to prevent the escape of any dust that may be discharged into the receptacle 2. 40 An outlet 6 is arranged at the center of one side of the receptacle and at the bottom thereof, and the bottom 7 of the receptacle is inclined from the rear and ends thereof down to the outlet 6, and the outlet is normally 45 closed by a door 8. A tank 9 is arranged on a bracket 10 at one end of receptacle 2 and is provided with a pump 11, whereby air may be compressed therein. A pipe 12 extends from the tank into the receptacle 2 and opens 50 into a spray 13, which is supported from the top of the receptacle by hangers 14.

A hood 15 is secured to and depends from one end of the platform 1 and is open only at

the bottom. The ends of this hood are provided with vertical slots 16, in which is 55 mounted a revoluble shaft 17, which extends through the center of a cylindrical brush 18. A collar 19 is loosely mounted on each end of the shaft 17 and is secured to one end of a chain 20. These two chains are secured to 60 substantially semicylindrical segments 21, fastened at the ends of a shaft 22, which is mounted in the walls of the hood 15 and has an operating-lever 23. A toothed segment 24 and a spring-pressed pawl 25 are provided 65 for locking the lever in adjusted position. A motor 26 of any suitable form is arranged upon the platform 1 and is adapted to transmit motion to the shaft 22 through a chain 27, which extends over a sprocket 28, ar- 70 ranged on the shaft 17, and a sprocket 29, secured to the shaft 30 of the motor 26. An outlet 31 is formed in the top of the hood 15 and communicates with a fan-casing 32, having an outlet-pipe 33, which opens into the 75 top of the receptacle 2. A rotary fan 34 is mounted within the casing 32 and is driven by the motor 26 through a chain 35, which is mounted on sprockets 36, located on the shaft 36^a of fan 32 and on the shaft 30 of the 80 motor 26.

In using the apparatus herein described water is placed in the tank 8, and air is compressed within the tank by means of the pump 11. A valve 37 is arranged within the 85 pipe 12, so as to prevent the compressed air from discharging the water through pipe 12 except when desired. When the vehicle is propelled forward, rotary motion may also be transmitted to the brush 18 from the motor 90 26. This brush, however, need not be in contact with the ground, but can be dropped into such position by swinging lever 23 so as to unwind the chains 20 from the segments 21. The motor 26 will also rapidly rotate the fan 95 34, and a suction will be established thereby from the hood 15, and dust, &c., brushed by the roll 18 will be drawn into the casing 32 and discharged through pipe 33 into receptacle 2. The air forced into the receptacle 100 will escape through the aperture-dome 3; but it will be understood that the moist sponge 5 will prevent the dust from passing outward therewith. When it is desired to remove the material from the receptacle 2, the valve 37 105 is opened and water is discharged under pneu-

matic pressure from the tank 9 to the spray 13, from which it is discharged upon the contents of the casing. The door 8 can then be opened, and the dirt, &c., which has accumulated within the receptacle can be removed without creating a dust. It will be seen that the hood 15 extends beyond one side of the platform 1, this construction being shown more particularly in Figs. 2 and 3, and therefore the brush 18 can be brought close to a curb and the gutters of a street cleaned as thoroughly as the road-bed.

Having thus described the invention, what is claimed as new is—

15 In a street-cleaning device, a supporting-frame, a hood depending from the frame and

formed with vertical slots and extending at one side beyond the frame, a brush-shaft vertically movable in said slots and having brushes, a second shaft extending through the upper portion of said hood and having segments, chains secured to said segments and connected with said brush-shaft, and a handle-lever fixed to one of the segments for operating the shaft, substantially as specified. 25

In testimony whereof I affix my signature in presence of two witnesses.

NAPOLEON ST. PETER, JR.
